UNITED STATES PATENT OFFICE.

CHARLES E. WEAVER, OF CHELSEA, IOWA.

CONTINUOUS RAIL.

No. 931,104.

Specification of Letters Patent.

Patented Aug. 17, 1909.

Application filed April 26, 1909. Serial No. 492,185.

To all whom it may concern:

Be it known that I, CHARLES E. WEAVER, a citizen of the United States, residing at Chelsea, in the county of Tama and State of Iowa, have invented a new and useful 5 Continuous Rail, of which the following is a specification.

The objects of the invention are, generally, the provision in a merchantable form of a 10 device of the class above described which shall be inexpensive to manufacture, facile in operation and devoid of complicated parts; specifically, the provision of a continuous rail joint adapted to maintain the 15 rail sections in alinement, to allow for expansion or contraction, and to maintain the ends of the rail sections at grade; other and further objects being made manifest hereinafter as the description progresses.

20 The invention consists in the novel construction and arrangement of parts herein-
after described, delineated in the accom-
panying drawings, and particularly pointed
out in that portion of this instrument where-
25 in patentable novelty is claimed for certain
distinctive and peculiar features of the de-
vice, it being understood that within the
scope of what is hereinafter thus claimed,
divers changes in the form, proportions,
30 size, and minor details of the structure may
be made, without departing from the spirit
or sacrificing any of the advantages of the
invention.

Similar numerals of reference are em-
35 ployed to denote corresponding parts
throughout the several figures of the draw-
ings.

In the accompanying drawings, Figure 1
40 shows my invention in top plan; Fig. 2
shows a horizontal, longitudinal section
thereof; and Fig. 3 is a side elevation, one
of the lower sections being spaced from the
remainder of the device in order to more
clearly reveal the structure.

45 In carrying out my invention, I provide
primarily a spacing block denoted generally
by the numeral 1. This spacing block 1 in-
cludes a base 2, which is of substantially the
same width as the flange of the rail with
50 which the spacing block is to be assembled.
Rising from the base 2 is a cruciform head
3 comprising longitudinal arms 4 extending
in the direction of the length of the track
and lateral arms 6 and 7 extending sub-
55 stantially at right angles thereto. The
longitudinal arms 4 are pointed at their ex-

tremities as denoted by the numeral 5. The lateral arm 6 has its face 8 disposed sub-
stantially at right angles to the direction of
the track. I further provide in carrying 60
out my invention, rail sections 14, the web
10 of which terminates at a short distance
from the end of each section, the said ends
of the rail sections, beyond the web thereof
being broadened as denoted by the numeral 65
11, to attain substantially the same thickness
as the cruciform head 3, measured through
the lateral arms 6 and 7 thereof. The adj-
acent faces of the portions 11 of the rail sec-
70 tion are cut away to form a seat, which con-
forms in outline to the face of the longi-
tudinal arms 4 of the spacing block. Por-
tions 11 of the rail section upon either side
of the seat 12, conform terminally to the 75
arms 6 and 7 of the spacing block against
which they are adapted to abut, one of said
portions terminating in a face 15 disposed
substantially at a right angle to the length
of the track, and parallel to the face 8 of 80
the arm of the spacing block, the end face
of the said section upon the other side of
the seat 12 terminating in a beveled face 16
disposed parallel to the face 9 of the spacing
block and adapted to be received thereby. 85
The ends 11 of the rail sections 14 are cut
away upon their lower faces as denoted by
the numeral 17, to rest upon the base 2 of
the spacing block 1.

When a railroad track is equipped with
the continuous rail joint of my invention, 90
the ends of the rails are rigidly supported
upon the base of the spacing block, and the
joints are not likely to be depressed even
under heavy traffic and prolonged use. By
pointing the extremities of the longitudinal 95
arms of the spacing block, and by providing
in the extremities of the rail sections, seats
12 conforming in shape to said arms, the
alinement of the track will be maintained,
the face 9 of the spacing block and the face 100
16 of the rail section, owing to their bevel,
serving to augment the action of the pointed
arms 12 in maintaining the alinement.

Although the pointed arms 4 and the bevel-
ed faces 9 and 16 serve to direct the move-
105 ment of the rail sections 14 in alinement with
each other, it is not desirable to have a bevel-
ed face upon the inner side of the rail lest
a wheel flange catch therein. To obviate this
difficulty, I have provided one of the lateral 110
arms 6 with faces 8 disposed substantially at
right angles to the direction of the track,

and it is obvious that with this construction the chance of a wheel flange entering the rail joint is reduced to a minimum.

The adjacent ends of the rail sections 14

- 5 may be spaced at any desired distance from the adjoining faces of the block 1, in order to allow for the expansion and contraction due to temperature changes. This spacing of the rail sections to accommodate the expansion 10 and contraction does not however produce a gap in the track, the arms 4 and the seats 12 providing for ample play without producing a break in the track line. The unpleasant click caused by the wheels of the car passing 15 from rail section to rail section will, when the device of my invention is employed, be entirely obviated, and, since the joints are firmly upheld, they are not likely to be depressed under protracted traffic, and there 20 will be no unpleasant sounds or jars when the railroad rolling stock passes from rail to rail.

The rail joints herein described tend to maintain the surfacing and the alinement of 25 the parts, and do away with the unpleasant rumble and clatter caused by low joints or by gaps between the rail ends, and it will be seen that the foregoing results are effected by a structure which is simple in form and 30 easily disposed in its place upon the ties, the device after having been once set in place, reducing to a minimum the expenses incident to a track repair and maintenance.

Having thus described my invention what

35 I claim as new and desire to protect by Letters Patent, is:—

1. A device of the class described comprising a cruciform spacing block having pointed longitudinal arms and a beveled trans-

verse arm; and rail sections having pointed 40 seats to receive the longitudinal arms and being beveled terminally to correspond with the transverse arm.

2. A device of the class described comprising a cruciform spacing block having longitudinal arms and being provided with a transverse arm having faces disposed substantially normal to the line of the track, and with a transverse arm having beveled faces; and rail sections having seats to receive the longitudinal arms, and being terminally faced to correspond to the transverse arms. 45 50

3. A device of the class described, comprising a cruciform spacing block having pointed longitudinal arms, and being provided with a transverse arm having faces disposed substantially normal to the line of the track, and with a transverse arm having beveled faces; rail sections having pointed seats to 60 receive the longitudinal arms, and being terminally faced to correspond with the transverse arms. 55

4. A device of the class described comprising a cruciform spacing block having longitudinal arms and transverse arms and rail sections having terminal seats to receive the longitudinal arms, the sections being terminally enlarged to correspond with the width of the block through the transverse arms. 65 70

In testimony that I claim the foregoing as my own, I have hereto affixed my signature in the presence of two witnesses.

CHARLES E. WEAVER.
